GAS TUBE BOILER CONSTRUCTION

Edwin Durham, Westfield, N. J., and Glen J. Schoessow, Barberton, Ohio, assignors to The Babcock & Wilcox Company, New York, N. Y., a corporation of New Jersey

Application November 14, 1949, Serial No. 127,136

7 Claims. (Cl. 122—512)

1

This invention relates to gas tube boilers of the waste heat recovery type and, more particularly, to a novel joint between the gas tube sheet, the boiler shell, and the hot gas duct or vestibule.

Gas tube boilers of the waste heat type generally include exterior shells, usually cylindrical, having tube sheets at either end supporting and positioning gas tubes disposed within the shell. The shell and its tubes may be positioned in the horizontal, vertical, or inclined position, depending upon the conditions involved. One end of the shell is connected to a duct, furnace, combustion chamber, or the like, arranged to supply hot gases to the tubes within the shell. The other end of the shell is connected to a duct, flue vestibule, or stack arranged to receive the hot gases discharged from the tubes.

The interior of the shell, externally of the tubes therein, is arranged to receive a liquid which is heated to a vapor by the hot gases flowing through the tubes. For this purpose, the shell interior is in communication with a liquid and vapor drum, and the liquid circulating path includes downcomers connecting the drum to the shell interior at the lower end and upcomers connecting the drum to the interior of the upper end of the shell.

In the attachment of flanged tube sheets to the shell, in prior art constructions where the shell has been extended beyond the planes of the tube sheet for welded attachment of the gas supply or exit ducts or vestibules, unsatisfactory stress conditions have been imposed on the joint. While the tube sheets and the pressure confining portion of the shell are subject to the cooling effect of the liquid confined by the shell and the tube sheets, the shell extensions projecting into the vestibules receive considerable heat from the high temperature gases, which later may be at temperatures in excess of 1000° F. The temperature differentials between the metal of the extensions and the metal of the weld zones thus impose strain conditions upon the joints which may result ultimately in weakening and failure of the joints.

To provide a more suitable construction adapted to the described conditions, the present invention provides a novel tube sheet and a novel joining of the tube sheet, shell, and gas conducting vestibule or the like. Specifically, the tube sheet is formed as an outwardly dished head or dome having its peripheral edge united to the end of the shell by a butt weld. The tube sheet, the boiler shell, and the joint therebetween are thus all exposed to substantially the same tem-

2

perature, that of the saturated steam and water within the shell. Consequently, the aforementioned temperature strains are substantially completely eliminated.

5 Additional means are provided to support the vestibules relative to the shell. These means may either support the vestibules on the tube sheets and interconnect the vestibules to the shell, or may support the vestibules directly on the shell.

10 Gas sealing means are provided between the tube sheets and the vestibules.

In one embodiment of the invention, lugs are welded to the exteriors of the tube sheets and the shell, and are interconnected by adjustable means, such as anchor bolts. A flat annular plate is welded to the lugs on each tube sheet, and the corresponding vestibule or gas duct is welded to this plate enclosing a substantial portion of the adjacent tube sheet. A ring is welded 20 to the tube sheet in such position that it has a close fit within the annular plate, and a flexible seal is provided between the ring and the circular plate to prevent gas leakage. For upright shell installations, to prevent steam entrapment 25 beneath the upper tube sheet, compartment baffles are installed in front of the risers to require the liquid and vapor to sweep over the upper part of the boiler. The anchor bolts, in conjunction with the annular plate welded to the vestibule, 30 act as stress transmitting means connecting the vestibule to means on the outer surface of the shell inwardly of the butt weld. Also, the annular plate and the lugs welded thereto provide means engaged between the vestibule and the outer surface of the tube sheet and operative to 35 resist outward movement of the tube sheet relative to the vestibule.

In another embodiment of the invention, the vestibules are formed with circumferentially spaced fingers fitting over and welded to the shell exterior inwardly of the joints between the tube sheets and the shell. An inwardly dished annular ring has its outer periphery welded to the inner surface of each vestibule outwardly of the 45 junction of the fingers therewith. The inner periphery of this ring is welded to the outer surface of the adjacent tube sheet. Under operative conditions, the fingers position the vestibule enclosures in substantially fixed relation to the shell, and the annular rings provide gas seals between the enclosures and the tube sheets while permitting a slight differential displacement therebetween without imposing destructive stresses thereupon. As in the first 50 embodiment, the inwardly dished ring acts as

means engaged between the vestibule and the tube sheet and resisting movement of the latter outwardly relative to the vestibule. This means, in conjunction with the fingers, is operative to resist movement of the tube sheet outwardly from the shell. The fingers act as stress transmitting means connecting the vestibule to the shell inwardly of the butt weld. In this embodiment, however, the inwardly dished ring also forms a major part of the gas seal between the vestibule and the tube sheet.

In both embodiments, ferrules are preferably placed in the tube ends to eliminate erosion of the tube inner surfaces at the entrance zone of high gas turbulence. With refractory material placed therearound, these ferrules limit heat input to the tube sheet.

With the foregoing in mind, it is an object of the present invention to provide a novel gas tube boiler construction.

Another object is to provide, in a gas tube boiler, a novel joining arrangement between the tube sheets, gas vestibules or ducts and the boiler shell.

A further object is to provide such a joint so located that the tube sheets, the shell, and the joint therebetween are all kept at substantially the same temperature.

Yet another object is to provide such a joint including means reinforcing the same against pressure stresses.

These and other objects, advantages, and novel features of the invention will be apparent from the following description and the accompanying drawings.

In the drawings:

Fig. 1 is a front elevation view partly in section, of a gas tube boiler embodying the invention;

Fig. 2 is a side elevation view of the boiler;

Fig. 3 is an enlarged partial longitudinal sectional view of one end of the shell and tube sheet enclosure, illustrating the novel joining of the shell, the tube sheet, and the hot gas vestibule or duct;

Fig. 4 is a partial side elevation view of the shell and vestibule of Fig. 3; and

Fig. 5 is a view, similar to Fig. 1, illustrating another embodiment of the invention.

Referring first to Figs. 1 and 2 of the drawings, a gas tube boiler 10, such as of the waste heat type, is illustrated as comprising an upright, somewhat inclined, pressure confining enclosure including a shell 15 and tube sheets 30, 30', and a liquid and vapor drum 25. Hot gases are conducted through the pressure confining enclosure by gas tubes 20 supported within shell 15 by securement to the sheets 30 and 30'. The hot gases, from a suitable source, enter a gas duct or vestibule 35 through an inlet opening 11, pass downwardly through tubes 20 to heat liquid and vapor within the enclosure, and exit into a second vestibule or duct 40 from which they pass through a suitable nipple or outlet connection 12. Inlet vestibule 35 may be provided with a suitable manhole 13 and be closed by a cap or cover 14. Exit duct or vestibule 40 is hopper shaped, tapering to a discharge opening 16.

Shell 15 is suitably supported on brackets, such as 17, and drum 25 on brackets 18. Drum 25 has a feed water inlet 21, steam outlet 22, vent 23, safety valve connections 24, and a gauge 26. Liquid, such as water, enters the bottom portion of the pressure confining enclosure from drum 25 through downcomers 21, and vapor or steam

passes from the upper end of the enclosure to drum 25 through upcomers 28, 28'. The upcomers 28' extend from the enclosure through vestibule 35 in heat exchange relation with the incoming high temperature gases. A drain 6 is provided for the pressure confining enclosure and a drain 7 for drum 25, both terminating in a T-connection 8.

Referring to Figs. 3 and 4, the tube sheet 30 comprises an outwardly dished or dome shaped member in which the ends of tubes 20 are secured by extending through holes 31 in the tube sheet and being welded to the latter as at 32. The inwardly extending periphery 33 of sheet 30 is secured to the end periphery 34 of shell 15 by a butt weld, as indicated at 45. The joint 45, as well as the joined ends of shell 15 and sheet 30, are thus subjected to the temperature of the liquid and vapor in the shell, which is the same temperature to which the main portion of the tube is exposed.

The inner end of vestibule 35 has circumferentially spaced fingers 36 with circumferentially extended outer ends 37, the fingers 36 embracing and engaging shell 15 inwardly of weld 45. An inwardly dished annular plate 50 encloses the space between tube sheet 30 and vestibule 35. To secure plate 50 to sheet 30 and vestibule 35, an annular weld deposit 51 having a horizontally plane upper surface is formed on the outer surface of sheet 30. A pair of weld deposits 53, 54 are then formed on the inner and outer peripheries of the inner surface, respectively, of plate 50, the outer surfaces of the weld deposits being flush with such periphery. Plate 50 is then placed with its inner periphery resting on weld deposit 51, and a welded joint 55 is formed to unite deposits 51 and 53 and the inner periphery of plate 50. Vestibule 35 is then slipped over the assembly and a weld 52 is formed to unite vestibule 35 to deposit 54 and the outer periphery of plate 50. Finally, fillet welds 56 are formed between extensions 37 and the outer surface of shell 15.

The plate 50, with its welded joints to the vestibule and the tube sheet, forms a gas tight seal between these elements. The plate 50 acts as a compressive stress transmitting means between the vestibule and the tube sheet and, in conjunction with fingers 36, acts to resist outward movement of the tube sheet from the shell. Ferrules 60 preferably are inserted in the ends of tubes 20 and refractory material packed around the ferrules within the vestibule and on the outer surface of tube sheet 30 in the same manner as will be described in connection with Fig. 5. The openings 57 formed between the circumferentially spaced fingers 36 allow access for inspection of the inwardly extended periphery 33 and welded joint 45.

When the shell 15 is arranged to extend upwardly as illustrated in Figs. 1 and 2, there is some tendency for vapor pockets to form under tube sheet 30. For the purpose, baffles 41 are arranged inwardly of the open ends of the risers or upcomers, such as 28. These baffles cause the liquid and vapor to sweep over the inner surface of the tube sheet before entering the riser tubes.

Fig. 5 illustrates a modified form of joining of the tube sheet to the liquid and vapor shell. In this construction, tube sheet 30 is the same as in Figs. 3 and 4, being an outwardly dished dome shaped member having its inner periphery 33' secured to the end periphery 34' of shell 15 by a butt weld 45'. Tubes 20 extend through holes 21

in sheet 30 and are secured to the sheet by welds 32.

U-shaped brackets 42 are mounted on the curved outer surface of sheet 30 and have outwardly opening slots 43 in their bases 44. Other U-shaped brackets 46 are secured to the external surface of shell 15 inwardly of weld joint 45. Bolts 47 extending through apertures in brackets 46 and through slots 43 secure the vestibule to the shell.

Brackets 42 also serve to support the gas duct or vestibule 35. For this purpose, annular plate 61 is mounted on brackets 42 and welded thereto as at 62. The vestibule 35 is supported on plate or ring 61 and a welded joint 63 forms a gas tight seal between the vestibule and plate 61, securing these two elements together. To complete the gas tight assembly of vestibule 35 to tube sheet 30, a ring 65 is secured to the tube sheet 30 by a weld 66, ring 65 being disposed within and closely adjacent the rear periphery of plate 61. A flexible sealing ring 67 closes the joint between rings 61 and 65. The ring 61 welded to lugs 42 acts with the latter as means engaged between the vestibule 35 and the tube sheet 30 operative to resist movement of the tube sheet outwardly relative to the vestibule. The lugs 42, ring 61, bolts 47, and lugs 46 form stress transmitting means connecting the vestibule to the shell inwardly of the butt weld.

To reduce or eliminate the scouring action of gases on the end portions of tubes 20, ferrules 60 are inserted into the ends of the tubes and disposed within vestibule 35. Refractory material 58 is arranged within the vestibule, around ferrules 60, and on the outer surface of tube sheet 30. This refractory prevents direct contact of the relatively high temperature gases with the outer surface of the tube sheet, thus contributing to the elimination of the above temperature differential strains. Baffle 41 may have a drain opening 68 in its lower wall 69.

The lower tube sheet 30' and the gas exit vestibule or duct 40 are secured to shell 15 in the same manner as described for upper tube sheet 30 and gas entrance vestibule or duct 35. In all cases, the described connections provide for limited relative movement of the joined elements to avoid destructive stresses.

While specific embodiments have been shown and described in detail to illustrate the application of the invention principles, it will be understood that the invention may be otherwise embodied without departing from such principles.

We claim:

1. In a gas tube boiler construction, a boiler shell arranged to form part of a liquid and vapor containing enclosure for the hot gas conducting tubes of the boiler; an outwardly dished tube sheet included in the enclosure and formed to have the gas tubes secured therein, said tube sheet having an inwardly extending peripheral rim; a continuous butt weld joint uniting the peripheral rim of said tube sheet to an end of said shell, said joint being located in heat transfer relation to the liquid and vapor space provided by said enclosure; a gas conducting vestibule extending outwardly of said tube sheet in communication with the gas tubes; stress transmitting means connecting said vestibule to the outer surface of said shell inwardly of said butt weld joint; and means engaged between said vestibule and the outer surface of said tube sheet and operative to resist outward movement of said tube sheet relative to said vestibule, said last-

named means comprising also gas-tight sealing means between the tube sheet and the vestibule.

2. In a gas tube boiler construction an upwardly extending boiler shell arranged to form part of a liquid and vapor containing enclosure for the hot gas conducting tubes of the boiler; an integral outwardly dished tube sheet included in the enclosure and formed to have the gas tubes secured therein, said tube sheet having an inwardly extending peripheral rim congruent with an end edge of the shell; a continuous butt weld joint uniting the peripheral rim of said tube sheet to the upper end edge of said shell; risers communicating with the upper end of said shell downwardly of said butt weld joint; and a baffle within the interior of said shell in front of the openings into said risers to force the liquid and vapor to sweep over the inner surface of said tube sheet and said joint to enter said risers to prevent formation of a vapor pocket under said tube sheet.

3. In a gas tube boiler construction, a boiler shell arranged to form part of a liquid and vapor containing enclosure for the hot gas conducting tubes of the boiler; an outwardly dished tube sheet included in the enclosure and formed to have the gas tubes secured therein, said tube sheet having an inwardly extending peripheral rim; a continuous butt weld joint uniting the peripheral rim of said tube sheet to an end of said shell, said joint being located in heat transfer relation to the liquid and vapor space provided by said enclosure; risers communicating with the upper end of said shell downwardly of said butt weld joint; a baffle within the interior of said shell in front of the openings into said risers to force the liquid and vapor to sweep over the inner surface of said tube sheet and said joint to enter said risers to prevent formation of a vapor pocket under said tube sheet; first anchor lugs secured to the exterior of said tube sheet; second anchor lugs secured to the exterior of said shell; means interconnecting said first and second anchor lugs; an annular plate mounted on said first anchor lugs; a gas conducting vestibule extending outwardly of said tube sheet in communication with the gas tubes and welded to said plate adjacent the outer edge thereof; a ring welded to said tube sheet adjacent the inner periphery of said annular plate; and means forming a gas-tight seal between said ring and said plate.

4. In a gas tube boiler construction, a boiler shell arranged to form part of a liquid and vapor containing enclosure for the hot gas conducting tubes of the boiler; an outwardly dished tube sheet included in the enclosure and formed to have the gas tubes secured therein, said tube sheet having an inwardly extending peripheral rim; a continuous butt weld joint uniting the peripheral rim of said tube sheet to an end of said shell, said joint being located in heat transfer relation to the liquid and vapor space provided by said enclosure; a gas conducting vestibule extending outwardly beyond said tube sheet in communication with the gas tubes and having its inner end secured to said shell; and an inwardly dished annular plate having its outer peripheral margin welded to the inner surface of said vestibule and its inner peripheral margin welded to the outer surface of said tube sheet to form a gas-tight seal between said tube sheet and said vestibule.

5. In a gas tube boiler construction, a boiler shell arranged to form part of a liquid and vapor

containing enclosure for the hot gas conducting tubes of the boiler; an outwardly dished tube sheet included in the enclosure and formed to have the gas tubes secured therein, said tube sheet having an inwardly extending peripheral rim; a continuous butt weld joint uniting the peripheral rim of said tube sheet to an end of said shell, said joint being located in heat transfer relation to the liquid and vapor space provided by said enclosure; a gas conducting vestibule extending outwardly beyond said tube sheet in communication with the gas tubes and embracing said shell inwardly of said joint; a welded joint securing the inner end of said vestibule to the outer surface of said shell; and an inwardly dished annular plate having its outer peripheral margin welded to the inner surface of said vestibule and its inner peripheral margin welded to the outer surface of said tube sheet to form a gas-tight seal between said tube sheet and said vestibule.

6. In a gas tube boiler construction, a boiler shell arranged to form part of a liquid and vapor containing enclosure for the hot gas conducting tubes of the boiler; an outwardly dished tube sheet included in the enclosure and formed to have the gas tubes secured therein, said tube sheet having an inwardly extending peripheral rim; a continuous butt weld joint uniting the peripheral rim of said tube sheet to an end of said shell, said joint being located in heat transfer relation to the liquid and vapor space provided by said enclosure; a gas conducting vestibule extending outwardly beyond said tube sheet in communication with the gas tubes, said vestibule having circumferentially spaced fingers embracing said shell inwardly of said joint; welded joints securing the inner ends of said fingers to the outer surface of said shell; and an inwardly dished annular plate having its outer peripheral margin welded to the inner surface of said vestibule and its inner peripheral margin welded to the outer surface of said tube sheet to form a gas-tight seal between said tube sheet and said vestibule; the spaces between said fingers forming access handholes.

7. In a gas tube boiler construction, a boiler shell arranged to form part of a liquid and vapor containing enclosure for the hot gas conducting tubes of the boiler; an outwardly dished tube sheet included in the enclosure and formed to have the gas tubes secured therein, said tube

5
10
